SHAWL OR THE LIKE

Peter Freund, Jr., Teaneck, N. J., assignor to
Peter Freund Knitting Mills, Inc., North
Bergen, N. J., a corporation of New Jersey

Application March 7, 1952, Serial No. 18,820

Term of patent 7 years

(Cl. D47—4)

To all whom it may concern:

Be it known that I, Peter Freund, Jr., a citizen of the United States of America, residing at Teaneck, in the county of Bergen and State of New Jersey, have invented a new, original, and ornamental Design for a Shawl or the like, of which the following is a specification, reference being made to the accompanying drawing, forming a part thereof, in which the figure is a plan view of one quarter of a shawl or the like showing my new design; the other three-quarters being identical therewith and arranged in proper relationship to complete the shawl.

I claim:

The ornamental design for a shawl or the like, substantially as shown and described.

PETER FREUND, JR.
